UNITED STATES PATENT OFFICE.

BENJAMIN F. CARPENTER, OF ROSELLE, NEW JERSEY.

IMPROVEMENT IN SPOOL-BOXES.

Specification forming part of Letters Patent No. 147,601, dated February 17, 1874; application filed December 29, 1873.

To all whom it may concern:

Be it known that I, BENJAMIN F. CARPENTER, of Roselle, in the county of Union and State of New Jersey, have invented a new and useful Improvement in Combined Thread Holder and Cutter, of which the following is a specification:

The invention will first be fully described, and then pointed out in the claims.

Figure 1 represents a vertical section of the apparatus, taken on the line *xx* of Fig. 1. Fig. 2 is a top or plan view with the cover off. Fig. 3 is a top view of the tension-disk on the stand in the thread-box. Fig. 4 is a cross-section through the cutter on the line *yy*.

Similar letters of reference indicate corresponding parts.

A is the box. B is the cover. C is a stand rigidly attached to the bottom of the box. The lower end of the stand is a socket, which receives a pivot-pin, D, which allows the box to be turned on the table E. F represents spool-pivots, which are fast in the bottom of the box. G are the spools of thread. H represents the thread. The stand C may be made of either metal, wood, or other suitable material. In this example of my invention I show a tension-disk, I, on the stand, having a hook or similar device for each spool. The thread from the spool may be carried to this disk, as seen at J, for giving a tension to it and guiding it from the spool. This arrangement is not indispensable, as the thread may leave the spool, as seen at K, and be carried up through the disk-plate L, which is designed to be about level with the top of the cover B. The holes in this disk are numbered on the top of this disk to indicate the number of the thread. M is a wheel formed of one or more plates, around the periphery of which is placed a close spiral

wire, N, for holding the thread when it is being cut. The thread, as it is carried up from the plate L, is passed between two of the convolutions of the spiral, and is compressed sufficiently to hold it for cutting. O is the cutter, which is semicircular in form, attached to the top of the wheel-disk M at its ends, as seen in Fig. 1, and is covered by the spiral P. This spiral is broken away in the drawing to show that the knife O is attached to the arch Q of the stand. The thread is carried over the spiral and forced down between two of the convolutions onto the edge of the cutter, and is thus readily severed. In thus cutting the thread the fingers of the operator are protected by the spiral.

Having thus described my invention, I claim as new and desire to secure by Letters Patent—

1. The combination, with a thread-cutter, O, of the circumjacent wire coil or protector P, applied as and for the purpose described.
2. The combination, with a thread-cutter, O, of a spiral wire, N, to hold the thread, in the manner set forth.
3. The combination, with a stationary thread-cutter holder, C, of rotary spool-box A B, as and for the purpose specified.
4. The combination, with spools G, arranged in a rotary spool-box, of a tension-disk, I, having a hole for each spool, an apertured disk-plate, L, thereabove, and the disk M, having spiral wire N, to maintain the thread at the proper tension at all points before being cut, in the manner described.

BENJ. F. CARPENTER.
